UNITED STATES PATENT OFFICE.

HENRY HIRSH, OF NEW YORK, N. Y.

PICTURE-HOLDING CAP FOR WATCH-CASES.

SPECIFICATION forming part of Letters Patent No. 276,408, dated April 24, 1883.

Application filed November 28, 1882. (Model.)

To all whom it may concern:

Be it known that I, HENRY HIRSH, of the city, county, and State of New York, have invented a new and Improved Picture-Holding Cap for Watch Cases, of which the following is a full, clear, and exact description.

The object of my invention is to provide a new and improved device for holding pictures, flowers, locks of hair, and other souvenirs on the cap which covers the works in watch-cases.

The invention consists in the combination, with a watch-case cap, of a watch-crystal held on the same, under which crystal the picture, lock of hair, or other memento or souvenir is placed. The crystal is preferably held on the cap by a bezel in the usual manner.

Reference is to be had to the accompanying drawings, forming part of this specification, in which similar letters of reference indicate corresponding parts in all the figures.

Figure 1 is a perspective view of a watch provided with my improved picture-holding cap, the back of the watch-case being shown opened. Fig. 2 is a cross-sectional elevation of the same. Fig. 3 is an enlarged detail cross-sectional elevation of the cap.

The cap A of a watch-case, which cap covers the works of the watch, is provided with an annular shoulder, α , on its outer or upper surface, against which shoulder α a bezel, B, holding a watch-crystal, C, of any kind, fits in the same manner as a bezel is held on the center D, for the crystal that covers the dial. A picture, E, a lock of hair, flowers, or any other souvenir, memento or keepsake is placed on the upper surface of the cap A, and the crystal C is held over it by the bezel B. The picture E, &c., can be seen whenever the back F is opened, which ordinarily covers the cap in the usual manner.

The bezel B and the crystal C can be held on the cap in any other suitable manner. The crystal C and the bezel B can easily be removed to place the picture, souvenir, &c., on the cap. The crystal C can be made curved, of a thin plate of glass, or it can consist of a thick plate of glass with beveled edges, or may have any other desired suitable shape. The bottom surface of the

crystal C can be made flat or concaved, as may be desired and according to the nature 50 of the article that is to be held on the cap.

I am aware that pictures have heretofore been held on extra rings or bezels hinged in watch-cases, and I am also aware that in stem-winding watches the back of the cap has been 55 cut out in the center and one or more pictures inserted in the recess cut out, the pictures being secured in place by a bezel, and I therefore lay no claim to such invention. In the construction last disclaimed, and also if the 60 extra ring first disclaimed, carrying the picture were employed as a cap covering the works, the picture cannot be inserted in the recess cut out of the back of the cap without opening the cap and exposing the works, which are thus apt to 65 be injured; nor can flowers or a lock of hair, or similar mementoes, be inserted in said recess without filling up the recess with some backing material to prevent the works being exposed. In this invention by taking off the 70 bezel the crystal can be removed, the picture or other memento placed on the back of the cap, the crystal placed over it, and secured in place by the bezel without exposing the works of the watch.

Having thus described my invention, I claim as new and desire to secure by Letters Patent—

1. The combination, with an ordinary closed watch-case cap covering and protecting the works, of a crystal secured to the back of the 80 cap by a bezel, substantially as described, whereby a space with a closed bottom is left between the back of the cap and the crystal for the insertion of pictures, flowers, hair, or other mementoes, without exposing the works 85 of the watch, as set forth.

2. The combination, with a watch-case cap, A, having an annular shoulder, α , of the bezel B, and the crystal C, extending over the back of the cap and held thereon by the bezel, substantially as described, and for the purpose set forth.

HENRY HIRSH.
